UNITED STATES PATENT OFFICE.

IRA EDWIN BURKEETT, OF MACON, GEORGIA.

LOADING AND DUMPING DEVICE.

Application filed April 2, 1924. Serial No. 703,767.

This invention relates to excavators and more particularly to a distantly controlled scraper hauling and dumping device adapted especially for use in connection with engineering projects involving the excavation of large or extended areas where it is necessary or convenient to convey and distribute or dump dirt or gravel to and from points remote from the source of locomotive power and control, such as: grading extensive areas, levee construction or repair, railroad cuts and embankments, canal construction, excavations for building foundations and the like.

The principal object of my invention is to provide a device of the character referred to in which an ordinary dirt scraper may be employed to collect dirt or gravel from any desired point within a defined area and convey and dump the same at any point within or outside the excavation or grading areas, either to distribute the same over such area or to dump it into suitable hauling vehicles for removal, without requiring the services of an attendant laborer at any point within the area under excavation.

Further objects of my invention are to provide a device of the character referred to which will be simple, durable and inexpensive in construction, use and transportation from place to place, in which an ordinary scraper may be readily connected or disconnected at the will of the operator.

The specific purpose of the invention is to provide mechanical means for drawing an ordinary scraper forwardly along a line from a variably fixable point, to fill the scraper and afterward convey it to any desired point along such line for dumping; to provide means for dumping the scraper at any point along the line of its forward movement over the ground, to provide mechanical means for returning the scraper by drawing it backwardly for repeated refilling and dumping at any point or points along its line of progressive movement over the surface of the ground, and to provide mechanical means for varying the fixable point on a line from which the scraper is drawn forwardly and backwardly, without requiring manual control or assistance for so doing.

The invention will be first hereinafter more particularly described with reference to the

accompanying drawings which are to be taken as a part of this specification, and then pointed out in the claim at the end of the description. 55

In said drawings, Fig. 1 is a perspective plan view of my device in position for use, illustrating the fundamental arrangement of the various elements and showing the means under power control for drawing the scraper forwardly and backwardly, the means for varying the fixable point along a line from which the scraper is drawn forwardly and backwardly and means for dumping the 60 scraper. In this view the scraper is shown in loaded position as it is drawn toward the point for dumping. 65

Fig. 2 is a side elevational view of the device illustrating a convenient arrangement of the various elements, showing the power unit, cable tower and an inclined platform by means of which the scraper is caused to empty its load into a dump-car, the operating cables being shown broken off. 70

Fig. 3 is a perspective view of one of the anchored posts with "dead-man" and brace, showing the pivotal arrangement of the pulleys over which the backing cable is passed; and 80

Fig. 4 is a perspective view of the travelling pulley-block, by means of which the point along a line from which the scraper is drawn forwardly and backwardly may be varied at will, the cables being fragmentarily shown. 85

Referring to the drawings, in which like reference numerals are used to designate corresponding parts throughout the several views, 5 denotes an ordinary steam engine or locomotive adapted under suitable lever control by an operator, to actuate associated rotatable cable drums 6, 7 and 8, each of which is provided with the usual dog and ratchet locking means and brake devices generally applied thereto for a well known purpose. 90

An ordinary scaffold or tower 9 of any preferred design is erected adjacent to the engine or upon a platform therewith, the latter, if desired, being mounted on railroad trucks, wheels or caterpillars for convenience in transportation and rapid transfer from place to place without necessity of dismantlement. The scaffold 9 is provided with elevated idling pulleys 10 and 11 located in its top portion 100

and may be adequately braced by adjustable tension bars and suitable guys (not shown).

Opposite the scaffold or tower 9, anchored posts 12 and 13 are fixed in the ground at any desired points and distance from said tower and from each other, said posts being rigidly secured in their respective places by means of anchor beams or "dead-men" 14 adjacently embedded in the ground, from which holding cables or brace ties 15 extend to the posts.

A pair of idling pulleys 16 and 17 are pivotally secured to the post 12, one above the other on a common swivel or pivotal axis, as shown in Fig. 3, thus independently adapting said pulleys to self-alignment with a cable passing thereover and readily permitting the two parts of the cable under operative conditions to assume variable angles with respect to the post.

20 A swivel block or idling pulley 18 is secured also to the post 13 either directly or indirectly by means of a short cable as preferred, the purpose of which will be herein-after fully explained.

25 A trolley or standing cable 19 is extended between the anchored posts 12 and 13 preferably with the minimum slack which the weight of the spanning cable will allow.

30 A strong traveller-block or cable-carrier 20 formed preferably with extremital idling pulleys 21 and 22 and an intermediate idling pulley 23, is mounted upon the cable 19 with the latter passing between the pulleys 22 and 23, thus adapting the block antifrictionally 35 to move along the span or length of said cable in either direction, the pulley 22 normally engaging the cable after the manner of an ordinary carrier or trolley, the pulley 23 engaging therewith only in case of rebound or backlash. A "pull" balancing yoke 24 is also provided on the block 20 by which one end of a pulling cable (to be hereinafter more specifically referred to) may be connected thereto.

40 A backing line or cable 25 is secured at one end to and wound upon the drum 6, its other or free end being passed over the uppermost idling pulley 11 on the scaffold and from thence to and over the self-aligning pair of idling pulleys 16 and 17 on the distantly anchored post 12 in the manner shown, after 45 which it is passed over the pulley 21 of the travelling block 20 and subsequently to an ordinary scraper 26, to the rear portion of which the cable is permanently secured by 50 any suitable attachment means.

55 To the forward end of the scraper 26, preferably by means of divided chain sections forming a yoke, the ends of which are secured to suitable reinforcing bracketed plates provided on either side thereof, one end of a pulling or hauling cable 27 is attached, said cable being passed over the pulley 10 on the scaffold and having its other end wound upon and secured to the drum 7, so that when said drum 60 is rotated so as to wind the cable thereupon, 65

the scraper will be drawn forward to scrape and load with earth and be afterward conveyed to the desired point for distribution or dumping.

A tension controllable holding line or cable 70 28 is secured at one end to and wound upon the drum 8, its other or free end being shown passed over or through an ordinary block or pulley 29 adjacent the scaffold, thence under the passage-way or track over which dump-carts or other hauling vehicles are drawn to receive loads from the scraper, to and over a similar block or pulley 30 on the opposite side of such passage-way, from which it is subsequently passed to and over the block or pulley 18 (above mentioned) on the distantly anchored post 13 and finally to the travelling block 20 with which it is connected by means of the pull-balancing yoke 24 as shown in Fig. 4 for holding said block 75 normally stationary under tension of the backing cable.

Should it be desired to haul the earth away from the excavated area, rather than distribute it for grading purposes, an inclined runway 31 may be employed, up which the scraper may be drawn to upset and unload into a dump-cart or car 32 drawn into position thereunder where it will receive the load.

80 The operation of my improved combined scraper and dumping device is as follows:

The scraper 26 is drawn backwardly to the point (on a line from the travelling-block 20) 85 at which it is desired to begin loading, by winding the backing cable 25 upon its drum 6, simultaneously allowing the drum 7 to run free and spend the pulling or hauling cable 27 as necessary. When the scraper has 90 thus been drawn to the point of loading, brakes are applied to the drum 7 and the ratchet locking means should then be set to prevent slippage of the drum, while drum 6 should be stopped and set to run free and spend the backing cable 25 as necessary. The 95 drum 7 is then caused to rotate and wind the pulling or hauling cable 27 thereupon, thus 100 drawing the scraper 26 forwardly, the latter being so balanced that the initial pull in a forward direction will cause it to tilt and 105 scoop up a load of earth the weight of which in turn shifts the center of gravity of the 110 scraper and causes it to tilt backward to conveying or hauling position, in which position it rides on a heel plate provided thereon for 115 such purpose. Continued pull of the hauling 120 cable as it is wound upon its drum causes the scraper to be conveyed (along a line from the travelling block 20) toward the tower 9 to the point for distribution or dumping. In 125 the particular arrangement of the apparatus as shown in Fig. 1, the loaded scraper is thus drawn forwardly onto and up the inclined platform 31, at the upper end of which it is automatically upset by reason of a precipitous decline in the platform surface, causing 130

the scraper to discharge its load into a waiting dump cart or car.

Simultaneously with the dumping of the scraper, rotation of the drum 7 is interrupted and brakes are applied to prevent slippage, after which said drum is set to run free and spend the hauling cable as necessary, while drum 6 is again rotated to draw the scraper backwardly to position for reloading in the 10 manner hereinbefore described.

When it is desired to shift the point along a line from which the scraper is drawn forwardly and rearwardly to dumping and loading positions, respectively, it is necessary only to move 15 the travelling block 20 in either direction along the standing cable 19. Should the point from which it is desired to continue operations lie between the anchored post 13 and the then present position of the block 20, the 20 drum 8 is caused to rotate so as to wind the tension or holding cable 28 thereupon, thus drawing the block 20 along the standing cable 19 toward the post 13 to the point desired, the backing cable 25 being simultaneously allowed to spend, after which the brake and 25 ratchet are set on the drum 8 to prevent its further rotation in either direction. Should the point from which it is desired to continue operations lie between the anchored post 12 and the then present position of the block 20, the 30 drum 8 is first released and then allowed to spend its cable 28, while the backing cable 25 is wound upon its drum, thus drawing the block 20 along the cable 19 toward the post 35 12 to the point desired, while the scraper is simultaneously drawn backwardly to loading position. The block 20 being thus moved to the desired point, the brake and ratchet are again applied to the drum 8 to prevent its rotation in either direction until it is again desired to shift the line of scraper operations.

It will, of course, be understood that while in the illustrated form or arrangement of my improved excavating apparatus or device, the scraper is adapted successively to dump its loads from the inclined platform into waiting dump carts or cars, it may be readily arranged to dump or distribute its loads at any point or points 50 along its variable lines of operation, without departing from the spirit and scope of my invention. An overhead tension controllable or stationary standing cable and trolley-carrier of any suitable type, such as shown and described, for instance, in my U. S. Patent No.

1,537,580 granted May 12, 1925, for improvements in excavators, may be conveniently employed for the latter purpose, the inclined platform, if desired, being wholly eliminated. Since various other changes in the details and arrangement of parts may be made without departing from the spirit and scope of my invention, I do not desire to be limited by the appended claim, to the specific construction and arrangement shown and hereinbefore described.

Having thus described my invention, what I claim as new and desire to secure by Letters Patent of the United States, is:

In a loading and dumping device, the combination of a scraper, pulling cables attached respectively to the front and rear of said scraper and secured to take-up and let-out devices located at a predetermined point for drawing the scraper forward and backward; a standing cable extended at a substantial angle to a mesne line of movement of the scraper between fixable anchorages remote from said take-up and let-out devices; a cable carrier mounted to move along said standing cable from end to end of the latter and having a pulley over which the backward pulling cable of the scraper passes for drawing the latter to its limit of backward movement, a pulley connected with one of said anchorages over which said backward pulling cable directly passes from the cable carrier to its take-up and let-out device; a holding cable having one end fixed to the cable carrier and its other end secured to a take-up and let-out device at said predetermined point of control for holding and shifting said carrier to the point along a line from which the scraper movement is desired; a pulley connected to the other of said anchorages over which said holding cable passes direct from said cable carrier to its take-up and let-out device for holding the carrier normally stationary from a point adjacent one limit of the latter's movement along said standing cable; means for upsetting and dumping the scraper along its variably directable line of movement; and power-driven means associated with said take-up and let-out devices for selectively operating the latter to reel and unreel said pulling and holding cables from said predetermined point of control remote from the operative area of said scraper, substantially as described.

In testimony whereof I affix my signature.
IRA EDWIN BURKETT.
